SEWING MACHINE AND TEMPLATE FOR
USE THEREWITH

John Stroop, New York, N. Y., assignor to Pad-Y-Wax Company, Inc., a corporation of New York

Application May 21, 1935, Serial No. 22,524

7 Claims. (Cl. 112—2)

The present invention relates to sewing machines and templates for use therewith.

In certain sewing operations it is necessary to stitch together two or more layers of fabric, along a more or less irregular seam to form an article in which all the layers are of identical shape. As examples of such articles, reference is made to gloves, mittens, pads, certain parts of garments and other articles which may be made up out of 10 two or more identical parts sewed together about the edge.

In the ordinary manufacture of articles such as referred to, each piece is usually cut to shape either by scissors or cloth-cutting machines, and 15 the two articles are basted or manually held together while the operator guides them through the sewing machine.

The present invention is more particularly devised to facilitate the formation of pads having 20 three plies of material and wherein the middle or inner ply consists of a layer of loosely carded fibres. When one attempts to sew three such layers of material in an ordinary sewing machine, the slippage between the layers is so great that 25 the upper layer of fabric shifts relative to the lower layer and the resulting product is not uniform, as to size and shape. By employing the template to be described herein, it has been found possible to operate the sewing machine at high 30 speed to stitch the three layers together to form the pads, and to do this without any preliminary basting of the parts together. The template contemplated herein is adapted to rest on the uppermost layer of fabric during the sewing operation and holds the upper layer against movement relative to the lower layers. The template also forms a convenient guide for the presser foot 35 of the sewing machine so as to determine the contour or configuration of the line of stitching. If desired, the template may be used in a combined sewing and shearing machine wherein the sewed fabric is sheared adjacent the line of 40 stitches.

Other and further objects will appear as the 45 description proceeds.

The accompanying drawing shows for the purpose of illustrating the present invention, two of the many embodiments in which the invention may take form, it being understood that the 50 drawing is illustrative of the invention rather than limiting the same.

In the drawing—

Fig. 1 is a transverse sectional view through a template;

Fig. 2 is a fragmentary transverse sectional

view through the sewing machine and template at an enlarged scale;

Fig. 3 is a fragmentary elevational view showing a detail;

Fig. 4 is a sectional view through a template of 5 modified form of construction; and

Fig. 5 is a perspective view illustrating the use of the template in a sewing machine.

The template shown in Fig. 1 has a relatively 10 stiff sheet metal body portion 10 with an upwardly bent flange 11. This body portion is slotted as indicated at 12 in Fig. 3 to facilitate soldering it to a grip or handle 14 and to a thin sheet metal plate 15. The thin plate 15 extends beyond the shoulder 11 and is provided with 15 downwardly pressed prongs or other forms of roughening as indicated at 16. The body portion of the template shown in Fig. 4 is in the 20 form of a sheet metal stamping 17 having a downwardly extending shoulder 17'. It is secured to the bottom plate 18 by a short tube 19. In either case, the lower sheet metal plate is 25 comparatively flexible and is able to bend downwardly away from the body plate, as will be clear from Fig. 2.

The plies of fabric to be used may be blanked out to be of approximate size and shape, or small enough to permit easy manipulation through a 30 sewing machine.

When the device is to be used, it is placed on 35 top of the layers of fabric and the margin or edge of the thin plate inserted under the presser foot indicated at 20. The template is completely disconnected from the work support W, and hence 40 can twist and turn as the configuration of the 35 design requires. The pressure on the presser foot bends the thin plate downwardly and compresses the filling material 21 (between the two 45 fabric layers 22 and 23), and the machine operated to sew. The feeder mechanism 24 advances the fabric and by moving the template as a guide a seam of the desired configuration is formed by the needle 25. This seam is free of wrinkles, 50 puckles, or the like. When the sewing machine is provided with shearing knives, such as indicated at 26 and 27, the article is trimmed close to the line of stitches. With an overlock stitch 55 sewing machine the shearing is prior to the stitching and the stitches enclose the sheared edge.

It will be understood that the template may 50 have various shapes and configurations, depending upon the shape of the seam which is to be produced. For producing a glove or mitten, the template will have the shape of the glove or mitten 55

desired, while for producing a pad, the template may be approximately square or rectangular with rounded corners.

It is obvious that the invention may be embodied in many forms and constructions within the scope of the claims, and I wish it to be understood that the particular forms shown are but a few of the many forms. Various modifications and changes being possible, I do not otherwise limit myself in any way with respect thereto.

What is claimed is:

1. A machine for securing together two or more layers of fabric, comprising a sewing machine having the usual work support, stitching needle, presser foot and feeder mechanism on which the lower layer of fabric bears, and a template completely disconnected from the work support and resting on the upper layer of fabric to move therewith and hold the fabric layers against relative slippage as the fabric is fed through the sewing machine by engagement of the feeder mechanism with the lower layer of fabric, the template having a thin flexible marginal portion extending under the presser foot and adapted to readily bend so that the entire pressure of the presser foot is transferred to the fabric adjacent the needle, the margin having an edge whose configuration corresponds to the contour of the seam to be sewed, the needle path being beyond the margin of the template, and a guide shoulder spaced uniformly from the edge thereof.
2. A sewing machine template adapted to rest on and move in all directions with goods during sewing and having a flexible element provided with a thin downwardly compressible, peripheral edge adapted to extend under the presser foot of a sewing machine and having a configuration to conform to the line of stitching to be formed, the template having a shoulder evenly spaced from the edge to engage the side of the presser foot of the sewing machine and prevent the shoulder from passing under the presser foot.
3. A sewing machine template having a thin, flat sheet metal plate adapted to rest on fabric, and a superposed, rigid body portion having a shoulder spaced inwardly from the edge of the plate, the body portion being secured to the plate at points spaced from the shoulder and the sheet metal plate being movable relatively to the shoul-

der so that the plate may yield relative to the body portion.

4. A sewing machine template having a thin, flat sheet metal plate adapted to rest on fabric, and a superposed, rigid body portion having a shoulder spaced inwardly from the edge of the plate, the body portion being secured to the plate at points spaced from the shoulder and the sheet metal plate being movable relatively to the shoulder so that the plate may yield relative to the body portion, the margin of the plate having a roughened lower surface.

5. A sewing machine template having a thin, flat sheet metal plate adapted to rest on fabric, a superposed, rigid body portion having a shoulder spaced inwardly from the edge of the plate, the body portion being secured to the plate at points spaced from the shoulder and the sheet metal plate being movable relatively to the shoulder so that the plate may yield relative to the body portion, and an upwardly extending grip carried by the body portion.

6. A machine for securing together two or more layers of fabric, comprising a sewing machine having the usual work support, stitching needle, presser foot and feeder mechanism on which the lower layer of fabric bears, and a template completely disconnected from the work support and resting on the upper layer of fabric to move therewith and hold the fabric layers against relative slippage as the fabric is fed through the sewing machine by engagement of the feeder mechanism with the lower layer of fabric, the template having a thin flexible marginal portion extending under the presser foot and adapted to readily bend so that the entire pressure of the presser foot is transferred to the fabric adjacent the needle, the margin having an edge whose configuration corresponds to the contour of the seam to be sewed, the template and presser foot having coating guiding means which, while permitting the bending of the template margin, insure that the needle path is a fixed distance beyond the margin of the template.

7. A machine such as claimed in claim 6 where-
in the template has peripherally arranged prongs
engaging the upper layer of fabric and holding
the layers in fixed rotation to each other.

JOHN STROOP.
